Primary Examiner — Cynthia Ramirez*Assistant Examiner* — Gino Colan(74) *Attorney, Agent, or Firm* — Andrew F. Young, Esq.; Lackenbach Siegel, LLP(57) **CLAIM**

The ornamental design for an inflation valve, as shown and described.

DESCRIPTION

This matter relates to PCT Ser. No.:PCT/US2014/17819 filed on Feb. 21, 2014, the entire contents of which are incorporated herein by reference.

FIG. 1 is a front perspective view of the embodiment of the present invention.

FIG. 2 is a top plan view of the embodiment shown in FIG. 1. FIG. 3 is a bottom plan view of the embodiment shown in FIG. 1, wherein the bottom side is fully disclaimed; and, FIG. 4 is a front elevation view of FIG. 1, a rear elevation view, a left elevation view, and a right elevation view being mirror images thereof.

The dash lines shown in the figures are for the purpose of illustrating portions of the inflation valve and form no part of the claimed design. The dash-dot-dot-dash lines in the figures are for the purpose of showing boundaries of the design and form no part of the claimed design.
